(57) **CLAIM**

The ornamental design for a laser measuring device, as shown and described.

DESCRIPTION

1. Laser measuring device

1.1: Perspective

1.2: Perspective

1.3: Front

1.4: Perspective

1.5: Back

1.6: Top

1.7: Right

1.8: Bottom

1.9: Left

The shadings indicated by thin lines are intended only to represent the three-dimensional shape of the surfaces of the design; left side view is omitted because it is mirror image of right side view; the oblique shade lines in the drawings are intended to show translucency; this article is a device that is used to measure angles and so on when setting a pipe.
